(57) **CLAIM**

The ornamental design for a M.O.L.L.E. system material with cut pattern, as shown and described.

DESCRIPTION

FIG. 1 is a front/right side isometric view of a first embodiment of a M.O.L.L.E. system material with cut pattern showing my new design.

FIG. 2 is a front elevation view of the M.O.L.L.E. system material with cut pattern of FIG. 1.

FIG. 3 is a partial cross-sectional view taken in the direction of line 3-3 of FIG. 2, the opposing partial cross-sectional view being a mirror image thereof.

FIG. 4 is a rear elevation view of the M.O.L.L.E. system material with cut pattern of FIG. 1.

FIG. 5 is a partial cross-sectional view taken in the direction of line 5-5 of FIG. 4.

FIG. 6 is a partial cross-sectional view taken in the direction of line 6-6 of FIG. 4.

FIG. 7 is a partial cross-sectional view taken along line 7-7 of FIG. 2.

FIG. 8 is a partial cross-sectional view taken along line 8-8 of FIG. 2.

FIG. 9 is a front/right side isometric view of a second embodiment of a M.O.L.L.E. system material with cut pattern showing my new design.

FIG. 10 is a front elevation view of the M.O.L.L.E. system material with cut pattern of FIG. 9.

FIG. 11 is a partial cross-sectional view taken in the direction of line 11-11 of FIG. 10, the opposing partial cross-sectional view being a mirror image thereof.

FIG. 12 is a rear elevation view of the M.O.L.L.E. system material with cut pattern of FIG. 9.

FIG. 13 is a partial cross-sectional view taken in the direction of line 13-13 FIG. 12.

FIG. 14 is a partial cross-sectional view taken in the direction of line 14-14 of FIG. 12.

FIG. 15 is a partial cross-sectional view taken along line 15-15 of FIG. 10; and,

(Continued)

FIG. 16 is a partial cross-sectional view taken along line 16-16 of FIG. 10.

The broken lines in the drawings define unclaimed boundaries of the claimed design.
